United States Patent Office.

JOSEPH H. SAUNDERS, OF JOHNSTON, RHODE ISLAND.

Design No. 4,462, dated November 8, 1870.

DESIGN FOR A PICTURE-FRAME.

The Schedule referred to in these Letters Patent and making part of the same

I, JOSEPH H. SAUNDERS, of Johnston, Rhode Island, have invented a new Design for Picture-Frames, of which the following is a specification.

In the accompanying drawing the form of my design is shown, in which—

A, B, C, D, &c., are the apertures for the pictures, the design shown being arranged for small card-pictures.

I construct my frames of wood, metal, or any other suitable material, but wood will probably be generally used.

I saw out the frame from the wood, which is prepared by taking two pieces of board and joining them at the cross $\times$, with the grain at right angles, by what is termed "halving." This is done to prevent a liability to warp.

Having sawed out the general form, the apertures A, B, C, &c., are made.

The glass and pictures are held in place by means of small cleats fastened to the back of the frame, or by some device similar to holding window-panes.

What I claim as my invention, and desire to secure by Letters Patent, is—

A design for a picture-frame in form of a cross, made of any suitable material, and arranged for holding twenty-two card-pictures, they also forming a cross, as above described.

JOSEPH H. SAUNDERS.
